CLAIM

We claim the ornamental design for a keychain spray misting fan, as shown and described.

DESCRIPTION

FIG. 1 is a perspective view of the keychain spray misting fan according to a first preferred embodiment of the present design;

FIG. 2 is a right side view of the present design, a corresponding left side view being a mirror image thereof;

FIG. 3 is a front view of the present design;

FIG. 4 is a rear view of the present design;

FIG. 5 is a top view of the present design; and,

FIG. 6 is a bottom view of the present design.

It being understood that the broken lines in FIG. 1 are for illustrative purposes only and form no part of the claimed design.
